[57] **ABSTRACT**

A driving drum or an idler drum for use with an article feeding belt for intermittently feeding a series of articles along a path so as to present them in succession to a plurality of operating stations where operations are performed on said articles in sequence. The belt is of non-stretch character and has a series of equally spaced article-receiving apertures of a shape to seat said articles. The drum carries on its periphery a series of plugs of a thickness at least equal to the belt thickness. The plugs are configured to fit snugly in the belt apertures when the belt is in a curved condition as it passes around the drum; and the leading and trailing edges of the plugs are profiled to enter and leave the belt apertures without interference. The plugs are secured in recessed flats on the drum periphery, the flats being of a size to accommodate the largest plugs for use with belts having apertures of a size to carry the largest of the articles to be treated. The plugs are easily replaced by smaller plugs for use with belts arranged to carry smaller articles.

DRIVING OR IDLER DRUM FOR ARTICLE FEEDING BELT

CROSS REFERENCE TO RELATED APPLICATION

This application is related to an application in the name of Elton G. Kaminski, Ser. No. 838,847, filed July 3, 1969, and is a continuation-in-part of application, Ser. No. 85,087, filed Oct. 29, 1970, now abandoned.

BRIEF SUMMARY OF THE INVENTION

This invention relates to a drum for use with an article feeding belt in an apparatus where a succession of like articles are fed along a path to a succession of operating stations where operations are performed on the articles. A machine of the type to which this invention relates is shown in U.S. Pat. to Kaminski et al., No. 3,231,065, issued Jan. 25, 1966.

In the apparatus of that patent, a stainless steel belt was provided and said belt had sprocket holes along its edges and was driven by a sprocket drum. The belt had apertures in which the articles were seated in order to be fed by the belt. The articles particularly disclosed were beverage can ends. An arrangement was provided for adjusting the position of the belt so that the articles carried thereby were properly oriented at the several operating stations.

In the Kaminski application, Ser. No. 838,847, mentioned above, the belt is disclosed as being of fabric impregnated with Neoprene or similar material and the belt had non-stretchable elements such as steel wires or cables embedded therein to give it non-stretch characteristics. The belt was internally toothed and was driven by a toothed drum. A more sophisticated apparatus for adjusting the position of the belt with respect to the operating station was disclosed.

According to the present invention, the belt may again be of fabric impregnated with Neoprene or the like and having non-stretchable elements embedded therein as in said copending application. The belt is designed (in the embodiment shown) to feed circular articles such as beverage can ends to operating stations for the attachment of pull tabs and scoring and the like. According to the present invention, the belt has no teeth and no sprocket holes and the article feeding apertures are relied upon for moving the belt in cooperation with plugs secured to the feeding drum, which plugs are arranged to fit snugly into the article feeding apertures.

Since from time to time articles of different sizes will have to be processed, it will be necessary to change belts, and to provide a plurality of belts, having apertures for each size of article to be processed. This, of course, necessitates changing drums, or the plugs or the drums which engage the article feeding apertures. According to the present invention, a plurality of sets of plugs, adapted to cooperate with belts having apertures of different sizes, may be provided; and it is a simple matter to remove one set of plugs and replace it with another.

BRIEF DESCRIPTION OF THE SEVERAL VIEWS OF THE DRAWING

FIG. 1 is a perspective view of a drum and a fragment of a belt in operative relation thereto.

FIG. 2 is an axial elevational view of the drum and belt.

FIG. 3 is an enlarged cross sectional view of a portion of the drum at which the belt is tangentially disposed with respect to a driving plug.

FIG. 4 is a fragmentary elevational view of a drum, with parts in cross section, showing the mounting of the plugs on the drum; and

FIG. 5 is a fragmentary plan view of the same.

DETAILED DESCRIPTION

- 10 The article carrying belt is indicated at 10 and is provided with a series of equally spaced circular apertures 11 in which the articles, for example can ends, are seated to be carried along to the operating stations. The drums are indicated at 12 and are mounted upon shafts 13. Adjusting means may be provided as at 14. It will be understood that the adjusting means may be as outlined in the above patent or in the above mentioned application. The adjusting means do not form a part of the present invention.
- 20 According to the present invention, at least the driving drum is provided on its periphery with a plurality of driving plugs 15. In the drawings, there are shown eight such driving plugs, such that as the belt passes around the drum 12, each article feeding aperture 11 of the belt is engaged by one of the driving plugs 15. It will be understood, however, that it is not necessary for each and every aperture 11 to be engaged by a plug and that four plugs 15 could be used instead of eight. It is only necessary that at least one plug be in full contact with an aperture at all times. That is, before the belt moves to a position where the aperture 11 in the belt disengages from a plug 15, another aperture must be fully seated on another plug 15.
- 30 The plugs 15 may simply be circular discs warped to fit on the surface of the drum. It will be understood that as the circular apertures 11 are bent in passing around the drum, the circular configuration becomes elliptical. The same would of course be true of the circular plug 15. Preferably, however, the plugs 15 will be turned, milled and contoured to the required configuration. It must be noted also that the leading and trailing edges of the plugs 15, as indicated at 15a and 15b, must be configured such that they engage and disengage the apertures 11 without interference. In other words, they must be profiled much as gear teeth. As a matter of assistance in aligning the belt with the drum, the plugs are preferably domed as at 16 and they may have a shank 17 which is pressed into a hole 18 in the drum. The thickness of the plugs 15 should be at least the thickness of the belt to insure proper gripping.

40 It is of course important that the drum which intermittently drives the belt be provided with the plugs as above described but it is also desirable that the idler drum or drums over which the belt passes employs the same plug construction. The use of plugs on the idler drum assures that there will be no slippage between the belt and idler drum to avoid abrasion of the drum and wear on the belt.

50 While in the embodiment described above, and shown in the drawings, the work pieces are circular, and therefore the apertures in the belt are circular, and the plugs are shaped to fit the said apertures in their distorted condition as they pass around the drum, it should be understood that the invention is adaptable to other shapes of work pieces. It is only necessary that the apertures in the belt have a configuration to seat the articles snugly, and that the plugs be shaped to fit

the belt apertures as they are distorted in passing around the drum, and are configured at their leading and trailing edges to engage and disengage the apertures in the belt without interference.

It is important that the plugs 15 be easily removed, and replaced with other plugs of different sizes, so that articles of other sizes may be accepted in different sized apertures in other belts. As best seen in FIGS. 4 and 5, the plugs are seated in flats which are milled into the periphery of the drum. One such circular flat is indicated at 19 in these Figures. The flats will be of a diameter to accept the largest plug, and smaller plugs may then be seated in the same flats. In the particular example shown, it will be noted that the plug 15 is smaller than the flat 19, so that a larger or smaller plug could be seated in the flat. The shank 17 is preferably threaded, and the plug is held in place by means of a washer 20 and nut 21. Because of the particular configuration of the plug described above, the plug must be properly oriented on the flat, and maintained in its properly oriented position. For this purpose the plug and the drum are provided with drilled holes, and a pin 22 is seated therein. Each set of plugs will be provided with shanks of identical diameter, and with holes for the orienting pins. Thus the changing of sets of plugs is a simple and speedy matter.

The endless belts must of course have a joint, and this is usually a welded joint. Flexing of the joint tends to ultimately break the joint. It is therefore important to minimize flexing by making the drums of relatively large diameter. Thus the drum should have at least one inch of diameter for each 0.001 inch thickness of the belt, i.e. where the belt is 0.015 inch in thickness, the drum should be at least 15 inches in diameter. The amount of flexing of the belt with these parameters will not adversely affect the joint.

It will be clear that numerous modifications may be made without departing from the spirit of this invention and therefore no limitations not specifically set forth in the claims should be implied and no such limitation is intended.

The embodiments of the invention in which an exclusive property or privilege is claimed are defined as follows:

1. In an apparatus having a belt, passing over at least two cylindrical drums, and having means for intermit-

tently driving one, at least, of said drums for feeding a series of articles along a path so as to present them in succession to a plurality of operating stations where operations are performed on said articles in sequence, said belt having a series of equally spaced article-receiving apertures of a shape to fit said articles, and having non-stretch characteristics; one, at least, of said drums having on its periphery a plurality of equally spaced recessed flats, each flat having a central, radial mounting hole, a plug having a threaded shank seated on each flat and held in place by a nut threaded onto said shank, each of said plugs extending radially outward beyond the projected circumference of said drum by an amount at least equal to the thickness of said belt, and of a configuration to fit snugly into the apertures in said belt when said belt is in contact with said drums, and the leading and trailing edges of said plugs being profiled to enter and leave said apertures without interference, and means to fix the orientation of each plug on its flat, the number of plugs on said drum being such that at least one of said plugs is in full engagement with a belt aperture at all times.

2. An apparatus according to claim 1, wherein said flats are recessed into the drum periphery.

3. An apparatus according to claim 1, wherein the orienting means for each plug comprise a pin seated in aligned holes in said flat and plug.

4. An apparatus according to claim 1, wherein the number of plugs on said drum is such that each aperture on said belt is engaged by a plug, as said belt passes around said drum.

5. An apparatus according to claim 1, said drum being intermittently driven and constituting the prime mover for said belt.

6. An apparatus according to claim 1, said drum being an idler.

7. Apparatus according to claim 1, wherein said belt passes around two drums, one being a driver and the other an idler, and both drums are provided with said driving plugs.

8. Apparatus according to claim 1, wherein said apertures are circular.

9. An apparatus according to claim 1, having one inch of diameter for each 0.001 inch of belt thickness, whereby to avoid excessive flexing of said belt.
